CLAIM

The ornamental design for a portion of a cabinet shelf, as shown and described.

DESCRIPTION

FIG. 1 is a top perspective view of a portion of a cabinet shelf;

FIG. 2 is a right side elevation view thereof, with a left side elevation view being a mirror image thereof; and,

FIG. 3 is a front elevation view thereof.

The dashed broken lines in FIGS. 1, 2 and 3 represent environmental subject matter and form no part of the claimed design.

1 Claim, 3 Drawing Sheets

FIG. 1

FIG. 2

FIG. 3

Adverse Decision in Interference

Patent No. D525,059, Bernard J. Golias, Sr., Bernard J. Golias, Jr., Robert J. Golias, Gray W. James, Gary R. Kish, PORTION OF A CABINET SHELF, Interference No. 105,651, final judgment adverse to the patentees rendered June 23, 2009, as to the claim.
(Official Gazette, January 12, 2010)
